UNITED STATES PATENT OFFICE.

CHARLES E. BENTLEY, OF NEW YORK, N. Y.

DESIGN FOR A BOTTLE.

SPECIFICATION forming part of Design No. 20,031, dated July 15, 1890.

Application filed June 3, 1890. Serial No. 354,142. Term of patent 7 years.

To all whom it may concern:

Be it known that I, CHARLES E. BENTLEY, a citizen of the United States, residing at the city of New York, county and State of New York, have invented and produced a new and original Design for a Bottle, of which the following is a specification, reference being had to the accompanying drawings, forming part thereof.

10 Figure 1 is a side view of a bottle embodying my design, and Fig. 2 is a plan view thereof, these two views being deemed necessary to fully illustrate the design.

15 The leading features of novelty of my design for a bottle or dressing-case ornament consist more particularly in the configuration of its lower body portion, which is surmounted by a comparatively long central neck or stem.

20 The body A of the bottle or ornament is surmounted by a central neck or stem a, which is shown slightly enlarged toward the top, but may be cylindrical or of like diameter throughout. The body is preferably made wider than it is deep and has an upper downwardly inclined or sloping face, which is formed with a series of alternate radial depressions 1 and elevations 2, which produce a circumferentially corrugated or wavy outline from the neck or stem to the outer margin, the corrugations increasing in width from the neck or stem to the margin. This mar-

gin or side edge is preferably formed, as seen best from the top and in Fig. 2 of the drawings, in a wavy or scalloped outline of alternating depressions 3 and convexed or rounded 35 projections 4. The lower face or side of the bottle or ornament extends downward and inward from the margin 3 4 to the bottom or base 5 of the bottle, which is somewhat larger in area than the cross-sectional area of the 40 neck or stem of the bottle. The lower face or side of the bottle-body is formed with alternating radial depressions 6 and convexed projections 7, which are directly below the upper depressions 1 and projections 2, whereby 45 the depressions 1 6, which nearly approach each other, together with the opposite projections 2 7, produce at the side margin of the body a series or chain of oval-like figures 8, which, while being rounded or convexed horizontally by the wavy marginal side outlines 4, are also preferably rounded over or convexed vertically, as shown in the drawings. 50

An ordinary cut-glass stopper is shown in the neck or stem of the bottle. 55

I claim as my invention—

The design for a bottle, substantially as herein shown and described.

CHARLES E. BENTLEY.
